UNITED STATES PATENT OFFICE

139,098

DESIGN FOR AN OWL COOKY JAR OR SIMILAR ARTICLE

Rudolph V. Ganz, Zanesville, Ohio, assignor to Shawnee Pottery Co., Zanesville, Ohio

Application March 1, 1944, Serial No. 112,755

Term of patent 14 years

(Cl. D58—25)

To all whom it may concern:

Be it known that I, Rudolph V. Ganz, a citizen of the United States, residing at Zanesville, in the county of Muskingum and State of Ohio, have invented a new, original, and ornamental Design for an Owl Cooky Jar or Similar Article, of which the following is a specification, reference being had to the accompanying drawings, forming part thereof.

Figure 1 is a front elevational view of an owl cooky jar or similar article showing my new design, and

I claim:

The ornamental design for an owl cooky jar or similar article, as shown.

RUDOLPH V. GANZ.
